UNITED STATES PATENT OFFICE.

HENRY BELL, OF NEW YORK, N. Y.

CAUSTIC-HOLDER.

SPECIFICATION forming part of Letters Patent No. 314,420, dated March 24, 1885.

Application filed December 13, 1884. (No model.)

To all whom it may concern:

Be it known that I, HENRY BELL, a citizen of the United States, residing at New York, in the county of New York and State of New 5 York, have invented certain new and useful Improvements in Caustic-Holders, of which the following is a specification, reference being had to the accompanying drawings.

This invention relates to caustic-holders, 10 and has for its object to provide a convenient and inexpensive caustic-holder which can be carried in the pocket, and by which the caustic when not in use is protected from atmospheric influences and yet may be quickly and 15 easily adjusted into position for use.

To such ends the invention consists in certain novel features, which will be first described, and then pointed out in the claims.

In the accompanying drawings, Figure 1 is 20 a side view of my device with the parts arranged ready for use. Fig. 2 is a similar view with the parts disposed as when not in use. Fig. 3 is a longitudinal section drawn through Fig. 2. Fig. 4 is a detail view of 25 the caustic-carrier, and Fig. 5 shows a modification.

The case A is made open at both ends, and is formed or provided at one end with an inwardly-turned flange, A', which reduces the 30 size of the opening at such end beyond the bore of the case, as will be most clearly seen in Fig. 3.

The carrier B is formed with the body portion B', the shank or stem B², and the tenon B³, arranged at the extremity of shank B², and made smaller than the said shank, as shown. The shank B² is made smaller than the body B', and the juncture of such portions forms a shoulder, B. The body B' is provided 40 with a socket or otherwise suitably adapted to receive and hold the caustic C. The cap D is fitted to be inserted into the large end of the bore of the case, and is provided with a mortise, D', formed from its inner end, and 45 adapted to fit over the caustic C and against the end of body B' when the carrier is inserted in case A, or on the tenon B³ when the device is adjusted into position for use.

When my device is not in use, the carrier

is drawn into the case, its shoulder b engaging flange A', and limiting its inward movement. The cap D is then inserted in the large end of the bore of the case, and its mortise D' fits over the caustic C, its end bearing firmly against the outer end of the body B'. By such 55 arrangement the caustic is protected from the air, and the body is braced firmly between the cap D and the flange A', so that it cannot vibrate or jar so as to break off or otherwise damage the caustic. When it is desired to 60 use the caustic, the cap is removed from the case and slipped on tenon B³, and the carrier is adjusted out to the position shown in Fig. 1.

It will be seen from the foregoing description that my carrier is adjustable into and out 65 of the case, and that the latter serves as a handle for the carrier in the use of same.

While it is preferred to use the construction shown, it is evident that the construction shown in Fig. 5 is within the broad principles of the invention. In this construction the case is open only at one end, and the carrier is adapted at one end to receive the caustic, and has at its other end a tenon fitted to the bore of the case. When in use, the tenon 75 is fitted in the case, and when not in use or closed the caustic-carrying end is inserted in the case, the carrier being provided with a shoulder or stop to limit the insertion of the caustic in the case. So in the modification, 80 the caustic-carrying end is capable of adjustment into and out of the case; but the construction shown in Figs. 1, 2, 3, and 4 is preferred, because by same body B' fitting snugly and sliding in the case prevents all liability 85 of the caustic coming in contact with the case and being broken while being adjusted into and out of position for use.

I claim—

1. The combination, in a caustic-holder, of 90 a case open at both ends and provided at one end with an inwardly-turned flange whereby the opening at such end is reduced in size, the caustic-carrier formed with a body portion fitted to the bore of the case, and a shank 95 made of a cross-section equal that of the reduced open end of the case, and a tenon formed on the extremity of such shank, and the cap

or head fitted to be inserted in the larger open end of the case or on the tenon of the carrier when the latter is adjusted out of or into position for use, substantially as set forth.

5. 2. The combination, with the case provided with a flange, A', and the carrier having a shoulder, b, of the cap adapted to fit snugly in the outer end of the case and against the caustic-bearing end of the carrier, whereby

the latter will be firmly clamped between the cap and the flange A', substantially as set forth.

In testimony whereof I affix my signature in presence of two witnesses.

HENRY BELL.
